UNITED STATES PATENT OFFICE

GEORGE ROSS-WATT, OF BRONX, NEW YORK

AUTOMATIC GAS CUT-OFF

Application filed March 12, 1930. Serial No. 435,270.

This invention relates to new and useful improvements in automatic gas cut off valves and more particularly to devices of this character which are especially adapted for use on 5 gas cooking ranges but it is to be understood that an automatic cut off constructed in accordance with this invention may be used in association with any type of gas burners for which the same is found adapted and desirable.

The primary object of this invention is to provide, in a manner as hereinafter set forth, an automatic gas cut off which is thermally actuated and which functions automatically 15 to shut off the supply of gas to the burner should the flame be extinguished as by an interruption in the supply pipe and which further embodies means whereby the valve will remain closed until manually opened to permit the passage of gas to the burner.

Another important object of the invention is to provide an automatic gas cut off of the character set forth which embodies a valve adapted to remain open for the passage of 25 gas to the burner only when said burner is lighted and which further embodies an arrangement which requires that the valve be manually retained in open position until the burner is lighted.

A still further important object of the invention is to provide an automatic gas cut off embodying manually operable setting or opening means in the form of a spherical 30 knob or handle adapted to prevent the valve being retained in open position by means other than the hands of the operator.

Other objects of the invention are to provide an automatic gas cut off of the character set forth which may be expeditiously mounted 40 in operative position for use on a gas range, which will be simple in construction, strong, durable, efficient in its use and which may be manufactured at low cost.

All of the foregoing and still further objects and advantages of the invention may become apparent from a study of the following specification, taken in connection with the accompanying drawings wherein like characters of reference designate corresponding

parts throughout the several views, and wherein:—

Figure 1 is a fragmentary view in perspective of one corner portion of a gas range showing an automatic cut off device constructed in accordance with this invention mounted in 55 operative position thereon.

Figure 2 is a view in vertical longitudinal section showing the cut off valve in closed position.

Figure 3 is a vertical longitudinal sectional view showing the cut off valve in open position to permit the flow of gas to the burner.

Figure 4 is a horizontal sectional view taken substantially on the line 4—4 of Figure 60 3 looking downwardly in the direction indicated by the arrows.

Referring to the drawings in detail, the reference character 1 designates the top of a conventional gas range having the burner 2 to which gas is supplied from the pipe 3 through the medium of the mixing tube 4.

The pipe 3 is in communication with the outlet port 5 located on one side of a gas chamber 6 formed on the metallic casing or 75 housing 7 which is suspended beneath the top 1 of the gas range. The chamber 6 is further provided with an inlet port 8 with which communicates the gas supply pipe 9 which is detachably secured thereto by the coupling collar 10. The inner end of the inlet port 8 is formed to provide a valve seat 11 upon which is engageable a reciprocating valve 12 rigidly mounted on a rod 13 which extends slidably through a closure plug 14 80 into the casing 7. The plug 14 is provided with suitable packing means 15 to prevent leakage of gas around the rod 13 from the chamber 6 into the casing 7.

The end portion of the rod 13 disposed 90 within the casing 7 is slidably supported through a bracket 16 mounted on one side wall of the casing 7. Fixed on the rod 13 in spaced relation to the bracket 16 is a collar 17 and a coil spring 18 encircles said shaft 95 and has one end impinged against the bracket 16 and its opposite end impinged against the collar 17 in a manner to urge said rod 13 and the valve 12 toward the seat 11 of the inlet port 8.

The end of the rod within the casing 7 is operatively connected through the medium of the pin and slot connection 19 to the lower end portion of a valve retaining lever 20 which is mounted for swinging movement in the casing 7 through the medium of the shaft 21 which is mounted rotatably in the sleeve 22 which projects inwardly from one of the side walls of the casing 7. The shaft 21 is provided with a polygonal end portion 23 which extends through an intermediate portion of the retaining lever which is fixed thereon through the medium of the set screw 24. The upper end portion of the retaining lever 20 is notched or recessed as at 25 for a purpose which will be presently set forth.

A thermal element designated generally by the reference character 26 is supported above the burner 2 to be played upon by the flame from said burner through the medium of a supporting arm or bracket 27 which is clamped on the mixing tube 4. The thermal actuating device 26 comprises a body portion 28 having a longitudinal passage 29 therein which communicates with a cylinder 30 formed in one end thereof. Threaded on the end of the member 28 in which the cylinder 30 is provided is a tube 31 which is filled with mercury and which has mounted therein a perforated plug 32 through which the mercury may pass from the tube 31 into the cylinder 30.

An actuating wire or rod 33 extends through the passage 29 into the cylinder 30 and has fixed thereon the piston 34 mounted for reciprocatory movement in the cylinder 30. The cable or rod 33 is flexible and extends slidably through a flexible housing 35 which has one end secured to the member 28 through the medium of the clamp nut 36 and its opposite end secured to the casing 7 through the medium of the clamping nut 37. The rod 33 projects into a cylindrical opening 38 in the casing 7 with which the housing 35 communicates. The head 39 is mounted for sliding movement in the cylindrical opening 38 and is fixed on the end of the rod 33 for actuation thereby. The head 39 is disposed in abutting engagement with the head 40 which is mounted on the adjacent end of a rod 41 slidably mounted in the supporting brackets 42 and 43 mounted on one of the side walls of the casing 7. A collar 44 is fixed on the rod 41 in spaced relation to the supporting bracket 43 and a coil spring 45 encircles said rod and has one end impinged against said bracket 43 and the opposite end impinged against the collar 44 in a manner to yieldingly urge the rod 41 and the head 40 into engagement with the head 39 on the flexible actuating rod 33. The rod 41 is operatively connected through the medium of the pin and slot connection 46 to the upper end of a pivotally mounted keeper 47 which is mounted for swinging

movement, as at 48, in the casing 7. The lower end of the keeper 47 is adapted for engagement in the recess 25 of the valve retaining lever 20 in the manner clearly illustrated in Figure 3 of the drawings for the purpose of maintaining the valve 12 disengaged from the seat 11. One end of the casing 7 is provided with an opening 49 whereby access may be had to the interior of said casing and said opening is closed by a removable closure plate 50. As clearly illustrated in Figure 4 of the drawings, the opening 49 extends on one end and one side of the casing and the closure plate 50 is of angular form and secured in place through the medium of the screws 51.

In use, when it is desired to light the burner 2 the operator actuates the retaining lever 20 through the medium of the spherical knob or handle 52 fixed on one end of the shaft 21 in a manner to swing said retaining lever 20 to the position indicated in dotted lines in Figure 2 of the drawings and in full lines in Figure 3. This moves the valve 12 to open position with respect to the seat 11 through the medium of the rod 13, as will be obvious, against the tension of the coil spring 18. Gas then flows from the pipe 9 through the chamber 6 and the pipe 3 to the mixing chamber 4 and the burner 2, and is ignited by the operator. When the flames play on the tube 31, the mercury therein is heated and expands and passes through the port in the plug 32 into the cylinder 30 of the member 28 in a manner to actuate the piston 34 and the flexible rod 33. As illustrated to advantage in Figure 3 of the drawings, the rod 33 will then move the head 39 inwardly and slide the rod 41 inwardly against the tension of the coil spring 45 and swing the keeper 47 in a manner to engage the same with the upper end of the lever 20 and in this manner retain the valve 12 in open position. Should the flames from the burner 2 be extinguished, the mercury in the tube 31 will cool and contract and thus the coil spring 45 will be permitted to shift the rod 41 in a manner to disengage the keeper 47 from the retaining lever 20 and the coil spring 18 will then move the valve 12 to closed position on the seat 11 and the supply of gas to the burner is thus cut off.

It will thus be seen that I have provided an automatic gas cut off whereby the passage of the gas to the burner is permitted only when the burner is functioning properly or when the valve is manually maintained in open position. The substantially spherical knob or handle 52 will effectively prevent the valve from being maintained in open position by extraneous means by persons who may wish to commit suicide. It is further understood that one of the thermal elements 26 is to be operatively associated with each of the burners on the gas range and the head 40 on the rod 41 is engageable with the head 39

of the actuating rod 33 of all of said thermal devices for actuation thereby.

It is believed that the many advantages of an automatic gas cut off constructed in accordance with this invention will be readily understood, and although the preferred embodiment of the invention is as illustrated and described, it is to be understood that changes in the details of construction may be had 10 which will fall within the scope of the invention as claimed.

What is claimed is:—

An automatic gas cut off for burners comprising a casing, a gas chamber mounted on 15 the casing having an outlet port and an inlet port provided with a valve seat, a valve disposed in the chamber and engageable on the seat to close the inlet port, a rod extending slidably into the chamber from the casing 20 and upon which the valve is mounted, a spring engaged with the rod to yieldingly maintain the valve in closed position, manually operable means for retaining the valve in open position comprising a retaining lever mounted 25 for swinging movement in the casing and operatively connected to the rod, an actuating handle located exteriorly of the casing and connected to the lever for manually swinging the same, a keeper mounted for 30 swinging movement in the casing and engageable with the retaining lever to maintain the same in operative position, thermally actuated means for shifting the keeper to permit the spring to release the same, said means 35 comprising a body member, said body member having a cylinder formed therein, a passage extending longitudinally therethrough and communicating with the inner end of the cylinder, a mercury filled tube closed at one 40 end mounted on the body member and communicating with the cylinder to permit the passage of the mercury from the container into said cylinder, means for mounting the body member and the container above 45 the burner in the path of the flames therefrom, a piston mounted for reciprocatory movement in the cylinder, a housing communicating with the passage in the body member and the interior of the casing, 50 a rod mounted for sliding movement through the housing and having one end extending into the cylinder and fixed to the piston therein, a head fixed on the opposite end of the rod and mounted for sliding movement in the casing, a spring controlled rod 55 mounted for sliding movement in the casing and having a head thereon engageable with the said head for actuation thereby, said spring controlled rod being operatively connected to the keeper.

In testimony whereof I affix my signature.
GEORGE ROSS-WATT.
